(57) **CLAIM**

The ornamental design for a decorative mold, as shown and described.

DESCRIPTION

FIG. 1 is a front view of a decorative mold;
FIG. 2 is a right side view thereof; the left side view, the top edge view, and the lower edge view being the same as FIG. 2;

FIG. 3 is a bottom thereof;

FIGS. 4 and 5 are isometric views thereof;

FIG. 6 is an isometric view of a first alternate embodiment of the decorative mold;

FIG. 7 is another isometric view thereof;

FIG. 8 is a front view of a second alternate embodiment of the decorative mold;

FIG. 9 is a right side view thereof; the left side view, the top edge view, and the lower edge view being the same as FIG. 9;

FIG. 10 is a bottom view thereof; and,

FIG. 11 is an isometric view thereof.

The broken lines in the drawings depict portions of the decorative mold that form no part of the claimed design. The pattern having an appearance of small circles illustrated in short broken lines on the inset areas of FIGS. 8 and 11 illustrate a surface texture, but the surface texture forms no part of the claimed design.
